UNITED STATES PATENT OFFICE.

ERNEST N. BRODERICK, OF INDIANAPOLIS, INDIANA.

BRUSH.

SPECIFICATION forming part of Letters Patent No. 639,348, dated December 19, 1899.

Application filed February 6, 1899. Serial No. 704,674. (No model.)

To all whom it may concern:

Be it known that I, ERNEST N. BRODERICK, of Indianapolis, county of Marion, and State of Indiana, have invented a certain new and useful Cleaning-Brush; and I do hereby declare that the following is a full, clear, and exact description thereof, reference being had to the accompanying drawings, in which like figures refer to like parts.

10 My invention relates to certain improvements in scrubbing or cleaning brooms, mops, and dusters.

A feature of my invention consists in the combination, with a tank-headed brush provided with outlets through the brush, of a hollow handle through which water may be passed and hollow adjustable joints connecting the tanks of the brush with the handle.

The construction and operation of my invention will be more clearly understood from the following description and reference to the drawings.

In the drawings, Figure 1 is a perspective view of my device. Fig. 2 is a longitudinal section of the same. Fig. 3 is a cross-section on the line A A of Fig. 2. Fig. 4 is a section of one of the adjustable hollow joints. Fig. 5 is an elevation of the device as used when dusting the tops of cabinets or moldings where it is necessary to reach upward to dust the top edge.

In detail, 1 is a tank, to which is attached the hollow casting 2, the upper end forming half the spherical joint 3, this casting being fastened to the top of the tank by the screws 4. The other half of the adjustable joint 3 connects by the hollow neck 5 to the joint 6, the end forming half of that joint. The detail of one of these adjustable joints, both of which are alike, is clearly set forth in Fig. 4. The hollow hemispherical portions are fitted together to form a ground or water-tight joint and are held together by a tightening-bolt 7, on which the parts of the joint rotate. When loosened, the handle may be turned to any angle in the same plane and then clamped as desired. Attached to the other half of the joint 6 is a hollow handle 8, to the end of which I have shown the hose 9 attached.

50 In the top of the tank I provide an opening

10, with a cap 11, through which opening I may pour in soap powder or any cleaning material desired. As a bottom for my tank I preferably use a perforated brush-top 13, (shown in Figs. 2 and 3,) making a water-tight joint 55 by inserting strips of rubber, leather, or other material 14 between the walls of my tank and the brush-top. Any other method of securing a tight joint between the walls of the tank and the brush-top may be employed.

60 On top of the perforated brush-top I place a slideable perforated plate 15, (shown in Figs. 2 and 3,) which is free to slide across the top and is held against this top by the strips 12, fastened to the walls of the tank. At one end 65 I secure a lug 16 to the top of said plate, to which I connect by means of a swivel-joint the bolt 17, which screws through the end wall of the tank, as shown in Fig. 2. The holes in the slideable plate are made to register with the perforations in the brush-top 14, so that by turning the screw 17 I may adjust the openings between the tank and the brush.

70 It will be seen from the foregoing description that by the use of both the adjustable joints I may set the handle at any angle to the brush, thus being able to use the brush for scrubbing the floor or for cleaning walls or windows, or I may by setting the handle as shown in Fig. 5 sweep off the dust from high 75 pieces of furniture without employing the use of a step-ladder.

80 When used for scrubbing, the hose can be connected to a hydrant, and thus supply the desired amount of water to the brush, making it unnecessary to dip the brush into the bucket or tub of water. In other words, my device is a self-feeding brush. Should I desire to use soapy water, I can insert through the openings 10 particles of soap or soap powder. In this way I get soapsuds, which I use 85 in scrubbing as it is needed, keeping the brush constantly supplied.

90 When my brush is used for dusting, the hose 9 may be connected with a compressed-air 95 tank, and in this way it loosens the particles of dust and blows them away.

95 It is not essential that a brush be used below the tank, as I may fasten on a mop or duster instead. When the tank is not needed, I 100

still have the very desirable feature of the adjustable handle. The tank, being small, does not interfere with the use of the brush.

What I claim as my invention, and desire 5 to secure by Letters Patent, is—

A cleaning-brush including a perforated top or back piece, suitable brush fibers covering one side thereof, a tank covering the other side of the top or back piece, a tubular handle, means for supplying a stream of water

through it, and a pair of hollow adjustable joints for connecting said handle to the tank, substantially as set forth.

In witness whereof I have hereunto affixed my signature in the presence of the witnesses 15 herein named.

ERNEST N. BRODERICK.
